UNITED STATES PATENT OFFICE.

JAMES W. HUBBARD, OF EAU CLAIRE, WISCONSIN.

COMBINED SIGNAL AND EMERGENCY TRAIN-STOPPING DEVICE.

1,361,862.

Specification of Letters Patent. Patented Dec. 14, 1920.

Application filed November 25, 1919. Serial No. 340,466.

To all whom it may concern:

Be it known that I, JAMES WARREN HUBBARD, a citizen of the United States, and a resident of Eau Claire, county of Eau Claire, State of Wisconsin, have invented a new and useful Combined Signal and Emergency Train-Stopping Device, of which the following is a full, clear, and exact description.

- 10 The present invention relates to a combined signal and emergency train stopping device and has reference more particularly to an association and coöperation of parts whereby a signal may be set up on a railroad track a short distance behind, or in the case of a single track system, also in front of the train which is standing still, to warn the engineer of a train approaching on the same track against proceeding farther; also 15 in lieu of the signal being disregarded by the engineer, to provide means as an emergency to prevent a collision by derailing the approaching train before it reaches the train that is at a standstill, and which the device 20 is intended to protect.

Various conditions and features are to be considered in realizing the advantages of the present invention, therefore it would seem to be in order to relate briefly the prevailing conditions which have proven inadequate as a practical solution of the problems involved. First of all when a train of cars has been brought to a standstill at a station or any other location along the line, and particularly where the train is to be maintained at a standstill for an unusual length of time, and especially where the train schedules require trains to be run more or less close together, it is customary 30 that the flagman, or some member of the crew of the train which has been brought to a standstill, walk up the track the proper distance behind the train or in front of the train if it happens to be a single track system, or if it is reasonable to expect an approaching train to come from the front, the flagman taking a red lantern with him at night as a signal medium, and a red flag in the day time. This present method is intended to signal the engineer of an approaching train in time enough for him to prevent 40 a collision, and while it has proven more or

less practical it is open to much criticism for apparent reasons, for instance, the safety of the train which is at a standstill is entirely in the hands of the flagman, and should he not perform his duty religiously a collision is likely to occur. Then again, although he may carry out his orders properly the engineer of the approaching train 55 may be at fault in failing to observe the flagman's signal or otherwise fail to bring his train to a stop in time to prevent a collision.

According to the present invention the disadvantages arising from the heretofore practised method are overcome in that aside from providing a most efficient signal, the invention is so constructed as to derail the approaching train should for any reason 60 the engineer fail to observe the signal and act accordingly.

The invention is applicable to railway systems in general, both electric and steam, and may be used in front or in the rear of a train 70 which is at a standstill to prevent a collision from the front or rear.

With these and minor features in view which will be referred to in the following description, the invention will be more readily understood upon reference to the accompanying drawings wherein an illustrative embodiment of the invention is shown, and in which—

Figure 1 represents a plan view of the arrangement and showing its relative relation to a car with which it is intended to be used.

Fig. 2 is a sectional view on the line 2—2 of Fig. 1.

Fig. 3 is a cross sectional view on the line 3—3 of Fig. 2.

Fig. 4 is a view of the wiring diagram.

Fig. 5 is a sectional view on the line 5—5 of Fig. 1.

Fig. 6 is a view on the line 6—6 of Fig. 5.

Fig. 7 is a plan view of the derailing device showing one form of signal embodied therein.

Fig. 8 is a cross sectional view through the 100 derailing device with the signal shown as in Fig. 7 embodied therein, and

Fig. 9 is a sectional view on the line 9—9 of Fig. 7.

Referring to the drawings by numerals of reference, in putting the invention into practice and so far as concerns the preferred embodiment thereof it should be considered that on each railroad car at both the front and rear, although this need not be controlling in every case, is carried the equipment for realizing the advantages of the idea. This equipment is preferably housed in a box like casing 1 which is mounted at any convenient place on the front or rear of the car such for instance as beneath the platform thereof. Mounted in the housing 1 transversely to a medial line through the car is a threaded shaft 2 which is journaled in the bearings 3 and 4 on opposite ends of the housing 1 so as to provide a horizontal shaft. Mounted on and fixed to the threaded shaft 2 preferably adjacent the journal bearing 4 is a reel 5 which is adapted to be rotated together with the shaft 2 by a spring motor 6, the spring of the motor being so positioned as to rotate when released, the reel 5 and the shaft 2 in an anti-clockwise direction so that the cable 7 or other flexible member secured thereto may be wound thereon after being unwound therefrom and carried rearwardly of the train along the track, the purpose of which will be presently described.

Fastened to the free end of the cable 7 is the combined signal and derailing device 8 which embodies substantially an oblong block of metal having a recess 9 in its bottom side made to receive the rail 10 and to which it may be clamped by the screw device 11 carried by the handle 12 to one corner of which is fastened the cable 7. This handle embodies a hand opening 13 and is constructed so that its weighted corner 14 will operate to move the handle in a clockwise direction when the tension of the cable 7 is relieved so that it will automatically manipulate the screw device 11 and clamp the derailing device to the rail. So long as the cable 7 is maintained taut under even a slight tension and by reason of the cable being fastened to a diagonally opposite corner of the handle from the weighted corner 14 the handle will be maintained in a position substantially as shown. When an abnormal pull or tension is imposed on the cable 7 the influence of the weighted corner 14 will be overcome thus turning the handle in an anti-clockwise direction releasing the derailing device through the screw device from clamping relation relative to the rail. The derailing device in so far as its derailing features *per se* are concerned may be constructed along conventional lines in that it will be provided with a deflecting flange which will deflect the wheels of the approaching train and accomplish the derailing object. The signal which is embodied in the derailing device may be realized in various ways, for instance

in the day time the derailing device may be provided with a socket 15 made to receive and vertically support the pole of a signal flag or the like. At night when a flag could not be used a light signal may be used instead of the flag. This light signal may be realized in various ways of which the illustrative embodiment shows two forms (see for instance Figs. 1, 2 and 3). In this particular form one end of the derailing device is made to support a light source such as an electric bulb which may be observed through openings 16, 17 and 18 in the top and two sides respectively of the device. Furthermore if desirable an opening may be provided in the back of the device making four openings in all. These openings may be observed by looking down on the device from a location between the derailing device and the car with which it is to be used, or from a location to the side of the device, and from the direction of an approaching train. The latter observation would be a signal to the engineer of the approaching train. All of the openings, or at least the opening 17 which is to be observed by the engineer of the approaching train should be covered by a red lens to represent a danger signal.

direction against the influence of the spring motor 6. As the flagman carries the derailing device along the track from the train and as stated, the shaft 2 is rotated, the sleeve 33 will be caused to travel toward the end of the shaft 2 which is supported in the journal bearing 3. Just as soon as it reaches a location adjacent the post 27, the contact finger 25 will contact with the finger 26 whereupon 5 the flagman will know that the derailing device has been carried to the limit of its functioning position beyond the train. The circuit from the conductor which is wrapped around the cable to the contact finger 25 is 10 made by connecting the wire through means of the member 34 to the shaft 2 and inasmuch as the opposite end of the contact finger 25 normally bears on the shaft 2 regardless of the position of the sleeve 33 on the shaft 20 15 2, a contact is always made between the conductor 19, the contact between the finger 22 and the plate 20, and with the contact finger 25.

It may so happen that the flagman may 25 neglect to remove the derailing device 8 from the track when the train is ready to proceed in which event when the train starts up the effect of an abnormal pull or tension is imparted to the cable 7 whereupon the handle 30 12 will be moved in an anti-clockwise direction which will release the screw device 11 and permit the derailing device to be released from the rail 10. In the meantime of course, the sleeve 33 will be adjacent to post 35 27, with the contacts 25 and 26 closed, this of course being the operative position of the parts. The derailing device in being dragged along the track will offer sufficient resistance to overcome the spring motor 6, and the resistance will also be sufficient to rotate the reel 5 and the shaft 2 and cause the sleeve 33 to travel farther on the shaft 2 in a direction toward the journal bearing 3. In so doing the sleeve will bear against the lever 34 which is presented in the path of the travel 40 of the sleeve and being pivoted as at 35 to a second lever 36, the air valve 37 may be manipulated through the toggle joint 38 whereupon the brakes may be automatically 45 applied with a warning to the engineer that the derailing device had not been removed and placed back in the box, whereupon the engineer may stop the train so that the flagman may get out and recover the derailing 50 device before serious injury to the same has been done.

Of course should the engineer of the approaching train disregard the signal on the derailing device and proceed ahead the derailing device will derail the train and at the same time it will more than likely be 55 completely demolished, and necessitate a new one being substituted in lieu thereof. It should be considered that the derailing device is only a small part of the apparatus

and a new one may be substituted without necessitating the installing of a complete apparatus. The demolishing of the derailing device and the expense incident to replacing the same will be slight compared to that 70 which would be necessary in repairing the train equipment and the injury to the passengers should a collision occur.

In connection with the closing of the circuit between the lead wire 24 and the plate 75 20 attention is invited to a modification of this detail which is shown in Fig. 6 wherein the circuit is closed to the plate 20 by means of a radially presented strip 20¹ and which is carried by a ring 20². This radial strip 80 20¹ extends to a point where a contact may be made as at the post 21.

In so far as concerns the operation and advantages of the apparatus the above description applies to all forms, however, as 85 to the signaling features, attention is called to Figs. 7, 8, and 9 wherein is shown a form which may be used in lieu of that shown in the other figures. For instance, instead of using the electric system of the train on 90 which the apparatus is used, the derailing device 8 may be equipped to accommodate a storage battery 39 with a light source 40 connected thereto by the leads 41, the light source being focused in a parabolic reflector 95 42 with a light projecting lens 43 provided on the side of the derailing device in position where it may be observed by the engineer of an approaching train. The lens of the light projecting opening may be supported in a cover 44 which is hinged as at 45. This lens should of course be red glass to indicate danger. This construction of the signaling features is used in connection with the derailing device having a handle 12 as 100 105 in the other form, the handle in this instance being equipped with a contact finger 46 which is made to contact with a similar contact plate 47 on the side of the derailing device 110 whereupon when the derailing device is placed on the rail 10 and the tension of the cable 7 brings the handle 12 into position as best shown in Fig. 9 the circuit between the light source and the storage battery will be closed by the contacts 46 and 47. Just as 115 soon as the tension of the cable is relieved the circuit will be broken.

Having thus described my invention what I claim as new and desire to secure by Letters Patent is as follows:—

1. In a device of the character described, a combined signal and derailing device normally carried by a car and connected therewith so as to permit of said device being positioned on the railway rail.
2. A combined signal and derailing device for railway rolling stock normally carried by the rolling stock and connected therewith so as to permit of said device being positioned on the railway rail.

3. A derailing device for railway rolling stock having a recess therein, and a light signal in said recess.
4. In a device of the character described, 5 a derailing device embodying in its construction an electric light signal, means connecting the derailing device with a car when the same is in use on a track and an electric circuit from the car to the electric light 10 signal thereof.
5. A derailing device for railway rolling stock having a chamber formed therein, and a self-contained electric light signal in said chamber.
- 15 6. In combination, a derailing device embodying in its construction a light signal, a reel supported on a car with which the derailing device is associated, a flexible member wound upon said reel and connecting 20 the derailing device with the car, a circuit connecting the light signal with the electric system of the car, and a circuit closer actuated by the unwinding of the flexible member on the reel for closing the 25 circuit to the light signal.
7. In combination, a derailing device adapted to be normally supported on a railway car but adapted to be positioned on the track a distance remote therefrom, a flexible 30 member connecting the derailing device with the railway car, a reel on which the flexible member is wound, a light signal on the derailing device, and means associated with the reel and controlled by the unwinding 35 of the flexible member therefrom for controlling said signal.
8. In combination, a derailing device adapted to be normally supported on a railway car but adapted to be positioned on the 40 track a distance remote therefrom a flexible member connecting the derailing device with the railway car, a reel on which the flexible member is wound, and a self contained electric light signal on the derailing 45 device.
9. The combination as set forth in claim 7 and in which the derailing device embodies a pivoted clamping member actuated by the tension of the flexible member connected thereto to release the clamping effect 50 of the said member.
10. In combination, a derailing device adapted to be normally carried in a housing on a railway car, a reel mounted with freedom 55 of rotation in said housing, a flexible member wound around said reel and connected to said derailing device, a shaft on which the said reel is mounted and fixed thereto, an electric light signal embodied 60 in said derailing device, a circuit between said electric light signal and the electric system of the railway car, means actuated by the rotation of the reel in a direction to unwind the flexible member therefrom, to 65 close the circuit between the electric system

of the railway car and the electric light signal on the derailing device, said circuit closing means operable to break the circuit thus closed when the reel is rotated in a direction to wind the flexible member thereof, 70 and means associated with the circuit closing means and the air brake system of the railway car to apply the brakes of the car when an abnormal length of the flexible member has been unwound from said reel. 75

11. The combination as set forth in claim 10 and in which the derailing device is provided with a pivoted handle having a screw device, said screw device adapted to be manipulated when the derailing device has 80 been placed on the track with the handle released to clamp the derailing device to a rail of the track.

12. The combination as set forth in claim 10 and in which the derailing device is provided with a pivoted handle having a screw device, said screw device adapted to be manipulated when the derailing device has been placed on the track with the handle released to clamp the derailing device to a rail of the 90 track, said flexible member being connected to said handle of the derailing device and adapted when an abnormal tension is imposed thereon to relieve the clamping action of said screw device for releasing the derailing device from clamping relation with the said rail.

13. In a device of the character described, a derailing device, means for locking the derailing device to a rail, a reel, a flexible 100 member adapted to wind on the reel and operatively connected with the locking means, and a spring motor associated with the reel, said motor adapted to function to wind the flexible member on the reel when the derailing device has been released from the rail, and adapted to impose a tension on the flexible member when the flexible member has been unwound from the reel with the derailing device clamped on the rail. 110

14. A derailing device embodying in its construction, a self contained electric light signal comprising an electric battery, and electric light source, with means for closing the circuit from the battery to the light 115 source.

15. A derailing device embodying in its construction a self contained electric light signal, comprising an electric battery and electric light source, a pivoted handle on the 120 derailing device, and means on the derailing device and on the handle adapted to close the circuit between the electric battery and the electric light.

16. The combination as set forth in claim 125 7, and in which the derailing device embodies means actuated by the tension of the flexible member connected thereto, to release the clamping effect of said means.

17. In combination with a railroad car, a 130

derailing device, a flexible member connected to the derailing device and the car, means for clamping said derailing device on a rail of the track, and means adapted to 5 apply the air brakes of the car should the car move forward when the derailing device is clamped to the rail.

18. In combination with a railroad car, a

derailing device, a flexible member connected to the derailing device and the car, 10 means coöperating with the connection of said flexible member through the car for signaling the engineer of the car should the car start forward with the derailing device clamped to the rail.

J. W. HUBBARD.
